UNITED STATES PATENT OFFICE.

LEWIS F. BETTS, OF BROOKLYN, NEW YORK, ASSIGNOR TO GEORGE B. WILSON, TRUSTEE, OF PHILADELPHIA, PENNSYLVANIA.

DESIGN FOR A LAMP-BODY.

SPECIFICATION forming part of Design No. 24,338, dated May 28, 1895.

Application filed March 2, 1895. Serial No. 540,366. Term of patent 7 years.

To all whom it may concern:

Be it known that I, LEWIS F. BETTS, a citizen of the United States, residing at Brooklyn, Kings county, in the State of New York, have 5 invented and produced a new and original Design for a Lamp-Body, of which the following is a specification, reference being had to the accompanying drawings, forming a part thereof.

10 Figure 1 is a front view, and Fig. 2 a side elevation.

The leading feature of my design consists in a horizontal cylindrical case or main portion, having a gracefully flared and beaded front face, a flared and beaded top, and a vertical fount with a conoidal top on such base.

Referring to the side view, Fig. 2, A is the main case, in the form of a horizontal cylinder with the back nearly plain, and beaded. The 15 upper half shows a horizontal row of round holes e. Each side is provided with a window B at the mid-height, of a form generally rectangular, with its horizontal dimensions a little greater than the vertical. The corners are 20 rounded. The rear side of the window shows conspicuously a vertical bead B', divided in three equal sections, one above the other. The front edge of the window shows at the 25 mid-height a smaller and shorter rectangular ornament B².

At the front of the case A is a gracefully flared enlargement constituting a face. It is 30 in four beads. The first, C', next to the case, is narrow, and has a diameter only a little greater than the case. The next C², is wide 35 and of greater diameter. The next, C³, is the narrowest of all. Its diameter is greater than the widest edge of C². The front bead, C⁴, is of intermediate width and of still greater diameter. All are gracefully rounded.

The top may be described as composed of 40 five members, one above the other. The lowermost, D', is trumpet-mouthed, the large end

uppermost. The next, D², is larger in diameter, but of less depth. The next, D³, is still 45 larger in diameter and of intermediate depth. The fourth, D⁴, is of less diameter, about equal to D³, and the uppermost, D⁵, is much smaller in diameter, and of less depth. All are 50 gracefully rounded. The lowermost, D', presents large circular holes d'; the next, D², a series of smaller holes d², and a series of small holes d³, appear in the junction of the third and fourth.

Below the case is a slightly contracted neck 55 E'; below this an upright cylindrical portion E², in which appears a circular disk F. Below this portion E², is an enlargement E³, in the form substantially of a frustum of a cone; below this a narrow bead of rectangular section E⁴, and below this a deep cylindrical fount E⁵, having its bottom edge slightly rounded.

The front view shown in Fig. 1 presents mainly the interior of the face. This is flared at a different angle near the periphery, and 60 presents a circular series of round holes c. The central portion of the front is deeply concaved, and presents four apertures c' in the lower half, c² in the upper half, and c³, and c⁴, at the mid-height on the right and left side 65 respectively. G is a wick tube extending up from below and showing parallel sides and a slightly rounded top. The portions of the 70 top and bottom which appear in this view above and below the face present the same 75 appearance as in the side view.

What I claim is—

The design for a lamp body substantially as shown and described.

In testimony that I claim the design above 80 set forth I affix my signature in presence of two witnesses.

LEWIS F. BETTS.
